MAGNETIC TAPE REEL ADAPTER

John C. Kountz, 1065 Van Dyke Drive,
Laguna Beach, Calif. 92651

Filed Aug. 31, 1970, Ser. No. 24,766

Term of patent 14 years

Int. Cl. D24—01

U.S. Cl. D26—14

FIG. 1 is a top perspective view of a magnetic tape reel adapter showing my design;

FIG. 2 is a top plan view thereof;

FIG. 3 is a side elevational view thereof;

FIG. 4 is a bottom perspective view thereof; and

FIG. 5 is a bottom plan view thereof.

I claim:

The ornamental design for a magnetic tape reel adapter, substantially as shown.
